DESIGN FOR WALL-PAPER.

Design No. 12,516, dated October 11, 1881.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,516, dated October 11, 1881.
Application filed August 25, 1881. Term of patent 34 years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

15 H, J, and L are the principal figures of this wall-paper.

The figure H might be termed an "oval rosette," being made with an oval center, open at its ends, and embraced by a border resembling 20 tongues of flame. From the upper end of this figure H projects a branch with three fan-like leaves thereon, and near the same is a flower-like figure, h. The figure I resembles the figure H very closely. It also has an oval center, open at the upper and lower ends, and has pointed projections resembling tongues of 25 flames, and has an upwardly-projecting stem, i, with leaves thereon similar to figure H. Whatever distinction exists between these two figures must be found in the central decoration of the inner oval and also in the specific ornamentation of the pointed projections, which in figure H contain each a central dash, while in figure I each is dotted, but substantially the 30 two figures are alike.

The figure J has around a central rosette a four-sided border, with rounded corners, and around the same pointed projections resembling those that embrace the figures H and I. 40 Two branches, n n, extend upward from the opposite sides of the figure J, while from the center of said figures projects upwardly a stem containing sundry leaves and leaf-like ornaments.

At each side of the figure J is a figure, M, 45 containing an oval center surrounded by oval beads, which, in turn, are surrounded by an undulating border with branches v, having leaves thereon, projecting from its sides, and with crowning ornamentation s at the top, as 50 shown.

Before the figure J is the figure L, which also has a central oval with some oval beads placed around it, and around these a main undulating border. Branches r, with leaves 55 thereon, project from the sides of the figure L, and on top is a stem, o, with leaf-like ornamentation. In outline there is practically no distinction between the figures L and M, the difference between these figures, if any, being 60 simply in the details of the interior ornamentation, as appears clearly from the photograph, but substantially these two figures are alike.

Smaller bug-like and some leaf-like figures and rosettes surround the more prominent figures H, I, J, L, and M, as shown.

I claim—

1. The design for a wall-paper, consisting of the figure H, substantially as shown.
2. The design for a wall-paper, consisting of the figure J, having ornaments n and j, substantially as shown.
3. The design for a wall-paper, consisting of the figure L, having ornaments r and o, substantially as shown.
4. The design for a wall-paper, consisting of the figures H I and ornament h, figure L, ornaments r and o, and figure J, having ornaments n and j, substantially as shown.
5. The design for a wall-paper, consisting of the figures H, I, J, L, and M, substantially as shown.

EDUARD LEISSNER.
